UNITED STATES PATENT OFFICE.

DANIEL H. KENDELHARDT, OF BROOKLYN, NEW YORK.

ELECTRIC TABLE ATTACHMENT.

1,184,539.

Specification of Letters Patent.

Patented May 23, 1916.

Application filed October 6, 1914. Serial No. 865,334.

To all whom it may concern:

Be it known that I, DANIEL H. KENDELHARDT, a citizen of the United States, residing at Brooklyn, in the county of Kings and State of New York, have invented new and useful Improvements in Electric Table Attachments, of which the following is a specification.

This invention relates to electric table attachments and it consists in the novel features hereinafter described and claimed.

An object of the invention is to provide an attachment especially adapted to be used in connection with extension tables for the purpose of giving a signal to summon a servant to the table or dining room when required. The attachment is intended to be used for operating an electric signal and consists of spring actuated drums journaled upon the table with wires connected to the drums one set of wires being provided with a push button and the other set of wires being provided with a plug adapted to be used in conjunction with a socket which is placed in the floor below the table. The drums are mounted in a frame for turning movement with relation to each other. The set of wires carrying the said push button are led to one end of the table and another set of wires is connected with the frame and the last mentioned set of wires is provided with a push button. Another set of wires is led to the opposite end of the table. The drum and drum frame are so arranged that when either one of the push buttons are operated an electric connection is established between the plug and the push button. The advantages incident to this arrangement of the wires and drums are that the table may be moved over the floor and at the same time the wires will be maintained sufficiently taut to prevent them from dragging on the floor also the table may be extended or contracted and the wires will be maintained in a proper taut position.

In the accompanying drawings:—Figure 1 is a side elevation of an extension table with the device applied thereto. Fig. 2 is a detailed edge elevation of the device. Fig. 3 is a transverse sectional view of the drums of the device. Fig. 4 is a detailed sectional view of one of the drums of the device cut on the line 4—4 of Fig. 3.

As illustrated in Fig. 1 of the drawings the device is applied to an extension table 1 of the usual form having removable leaves

2. Brackets 3 are secured to the under portion of the frame of the table 1 and carry a shaft 4. The shaft 4 is a good conductor of electricity. Outer disks 5, also good conductors of electricity are mounted at the end portions of the shaft 4 between the brackets 3 and the said disks 5 have electric contact with the shaft 4. The disks 5 are provided at their inner sides and in the vicinity of their edges with annular grooves 6. A disk 7 is mounted at the intermediate portion of the shaft 4 and is insulated from the same by means of a sleeve 8. If desired conducting plates 9 may be provided at the opposite sides of the disk 7. The disk 7 is provided at its opposite sides and in the vicinity of its edges with annular grooves 10. Drums 11 are turnably mounted between the disks 7 and 5 and the edge portions of the said drums are received in the grooves 10 and 6 respectively of the said disks as best shown in Fig. 3 of the drawings. The drums 11 are formed from insulating material and the said drums are provided at their edges with plates 12 which have contact with the bottoms of the grooves 10 and 6 as shown in Fig. 3. Spiral springs 13 are located within the drums 11 and are connected at one end with the shaft 14 and at their other end with the drums 11.

Wires 14 are connected one with the disk 7 and the other with one of the disks 5 and the said wires are trained through a guide 15 attached to the under portion of the table 1 and are connected to a push button 16 of any usual pattern. Wires 17 are connected at one end with the plates 12 mounted upon one of the drums 11 one wire being connected with that plate which has contact with the disk 7 and the other wire being connected with that plate which has contact with the adjacent disk 5. The other ends of the wires 17 are connected with a push button 19 and the intermediate portions of the said wires are trained through a guide 18 mounted at the opposite end portion of the table 1 from the guide 15. Wires 20 are connected with the plates 12 mounted upon the other drum 11 and the said wires 20 are also connected with a plug 21 which is adapted to be inserted in a socket (not shown) placed in the floor of the room. It is of course understood that the said socket is connected in an electric circuit and is provided with a bell or other signal.

When the plug 21 is in the socket, hereto-

fore referred to, and when the push button 16 is closed the current passes along one of the wires 20 from the plug 21 to the outermost plate 12 upon one of the drums 11. 5 The current then passes along the adjacent disk 5 to the shaft 4 thence along the said shaft to the other disk 5 thence along that wire 14 which is connected with the last mentioned disk to and through the push 10 button 16 thence along the other wire 14 to the disk 7 and thence through the other plate 12 mounted upon the first mentioned drum 11 and along the other wire 20 back to the plug 21. Thus the circuit is completed and 15 the alarm which is connected with the socket is sounded.

If the push button 19 is closed the current passes from the plug 21 along one of the wires 20 as hereinbefore described to one 20 of the drums 11 thence along the adjacent disk 5 to the shaft 4 thence along the shaft 4 to the other disk 5 thence along one of the wires 17 to the closed plug 19 thence along the other wire 17 to the plate 12 mounted 25 upon the drum 11 having contact with the disk 7 thence along the disk 7 and the plate 12 upon the other drum to the wire 20 and thence along the said wire 20 back to the plug 21. Therefore it will be seen that the 30 alarm may be sounded or given by a person at either end of the table 1. Inasmuch as the brackets 3 are fixed with relation to the guide 15 no provision is made for taking up any slack which may occur in the wires 35 14. But inasmuch as the device is applied to an extension table means is provided for taking up any slack which may occur in the wires 17 when the leaves 2 are removed from the table 1. This is done by means of the 40 spiral spring 13 which is located within the drum 11 to which the wires 17 are attached. As the wires 17 become slack the tension of the spring 13 located in the said drum causes the said drum to turn whereby the wires 17 45 are wound upon the drum and thus the said wires 17 are maintained in a taut condition

and are prevented from sagging or coming in contact with the floor. Also any slack which may occur in the wires 20 is taken up 50 by reason of the fact that said wires are connected with the other drum 11 and the spring 13 in the last mentioned drum will rotate the said drum and wind the wires 20 thereon whereby the said wires 20 will be maintained 55 taut and the table 1 may be moved with relation to the socket 20 when the socket is in engagement with the plug as indicated in Fig. 1 of the drawings. By this arrangement it will be observed that the leaves 2 may be readily detached from the table or 60 inserted therein and at the same time the wires will not sag and become tangled in objects upon the floor of the room. Furthermore the table may be readily moved within 65 the length of the wires 20 so that the floor of the room may be swept or cleaned and the wires 20 will not sag or fall upon the surface of the floor.

Having thus described the invention what is claimed is:—

1. A device as described comprising spring actuated drums, said drums being turnable with relation to each other and means located at the drums for establishing electric connection between the drums.

2. In a device of the character described a shaft, outer disks mounted upon the shafts and electrically connected with the same, an inner disk mounted upon the shaft and insulated from the same, drums turnably mounted between the outer and inner disks, springs connected with the shaft and connected with the drums, and means carried by the drums for establishing electric connection between the outer and inner disks.

In testimony whereof I affix my signature in presence of two witnesses.

DANIEL H. KENDELHARDT.
